UNITED STATES PATENT OFFICE.

MICHAEL A. DROITCOUR, OF DELPHOS, OHIO.

BED AND CYLINDER DRIVE FOR PRINTING-PRESSES.

1,171,843.

Specification of Letters Patent. Patented Feb. 15, 1916.

Application filed January 18, 1915. Serial No. 2,964.

To all whom it may concern:

Be it known that I, MICHAEL A. DROITCOUR, a citizen of the United States, and a resident of Delphos, in the county of Van Wert and State of Ohio, have invented a certain new and useful Bed and Cylinder Drive for Printing-Presses; and I do hereby declare the following to be a full, clear, and exact description of the invention, such as will enable others skilled in the art to which it appertains to make and use the same, reference being had to the accompanying drawings and to the characters of reference marked thereon, which form a part of this specification.

This invention relates to means for synchronizing the movements of the cylinders and beds of printing presses during predetermined portions of the movements thereof. The primary object of my invention is the provision of a novel and improved mechanism of the character described, which is operable to drive the bed during a portion of each stroke of uniform speed with the cylinder, and to slow down and stop the bed at the end of each stroke, after which it is started back with accelerating speed until it is again traveling at uniform cylinder speed.

Further objects and advantages of the invention will be apparent from the following detailed description thereof.

The invention is fully described in the following specification, and while, in its broader aspect, it is capable of embodiment in numerous forms, a preferred embodiment thereof is illustrated in the accompanying drawings, in which,

Figure 1 is a side elevation of a mechanism embodying my invention with parts broken away. Fig. 2 is a section thereof on the line $v-v$ in Fig. 1. Fig. 3 is an enlarged section on the line $w-w$ in Fig. 1. Fig. 4 is a longitudinal vertical section on the line $x-x$ in Fig. 2 with parts broken away, and Fig. 5 is a perspective view of the mechanism with parts broken away and in section and with one side portion separated from the remaining parts to disclose parts of the mechanism which would otherwise be obscured.

Referring to the drawings, 1 designates a press frame which is provided longitudinally thereof between its sides with a plurality of rails 2 (three in the present instance), the top surfaces of which slidably support

and guide the reciprocatory movements of a runner frame 3. Mounted on the runner frame 3 for reciprocatory movements relative thereto lengthwise of the frame 1 is the form bed 4, which travels under a cylinder 5, the shaft 6 of which is suitably journaled in bearing blocks 7 in the upper portions of the frame sides. The bed 4 is provided on the under side thereof with a plurality of runners 8, which rest upon the runner 3 and travel in respective guide-ways 9 therein.

The cylinder bearings blocks 7 are vertically adjustable in the respective frame sides to permit a raising and lowering of the cylinder 5 at predetermined points in each cycle of operations of the press whereby the cylinder will have contact with a type form on the bed 4 during movements of the bed in one direction only, as is well understood in the art.

Each bearing block 7, in the present instance, is yieldingly supported by a rod 10 the lower end of which rests upon a coiled compression spring 11 suitably mounted in the frame side. Each block 7 is also connected by rods 12, 12 to a subjacent bearing block 13, which is guided for vertical movements within an opening 14 in the lower portion of the associated frame side and forms the lower bearing or pillow block for an end of a rock-shaft 15, which is mounted transversely of the frame beneath the cylinder 5. The upper thrust of each end of the shaft 15 is opposed by an impression adjustment block 16, which is mounted for vertical adjustment in the frame side. The rock-shaft 15 has the portions of its ends, which are in bearing contact with the blocks 13 and 16, provided with semi-circular cam bearing surfaces which, upon a rocking of the shaft, act to cause one of said blocks to move toward or away from the other, as is apparent. It is thus evident that a rocking of the shaft 15 in a direction to effect a separation of the bearing blocks 13 and 16 will effect a lowering of the cylinder 5 to impression receiving position with relation to the bed 4, and that a rocking of the shaft 15 in the opposite direction will permit a raising of the block 13 and cylinder 5 under the action of the spring 11.

The cam-shaft 15 is provided with a rocker-arm 17, which is connected by a rod 18 to a lever member 19, which is vertically disposed and pivoted at its lower end to a

frame part 20. The lever 19 is provided intermediate its ends with a roller 21 that travels in a cam groove 22 on a side of a spur gear 23, which gear is mounted on a shaft 5 projecting from a bearing arm 24 of the frame. The gear 23 meshes with and is driven by a small gear 25 on the main drive shaft 26 of the mechanism. The drive shaft 26 is journaled transversely of the frame in 10 suitable bearings therein and carries a belt pulley 27 at one end without the frame 1, if it is desired to utilize a belt drive for the shaft.

While I have shown and described a 15 particular form of mechanism for intermittently raising and lowering the cylinder, it will be understood that such mechanism considered alone forms no part of the present invention and that the only purpose of 20 showing the same herein is to illustrate one mechanism for controlling the raising and lowering of the cylinder.

The gear 23 carries a crank-pin 28 on the side thereof opposed to the cam groove 22, 25 and such crank-pin in turn carries a block 29, which has reciprocatory movements in a vertical slide-way 30 that is provided on the runner 3. It is thus evident that a rotation of the gear 23 will impart positive 30 predetermined reciprocatory movements to the runner 3 through the medium of the slide-block 29 and slide-way 30, and also that upon a reversal of each stroke of the runner 3 its speed will be accelerated to 35 maximum speed and then slowed down and stopped preparatory to reversing its stroke, as is well understood in the art, such movement and manner of effecting the same being old in connection with printing presses 40 of the bed and cylinder type.

The runner 3 carries, in the present instance, a pair of pinions 31, one near each side thereof, and each of these pinions meshes at its lower side with a fixed rack-bar 32 attached to the side of the adjacent frame-rail 2, and meshes at its upper side with a rack-bar 33 on the under side of the bed 4. It is thus evident that the bed 4 will be caused to have reciprocatory movements with the runner 3 and that each stroke of the bed 4 will be twice the length of the corresponding stroke of the runner 3. For instance, should the throw of the crank-pin block 29 on the gear 23 be sufficient to 55 impart an eighteen inch stroke to the runner 3, the rack and pinion connection 31, 32 and 33 between the runner and bed 4 would cause the bed to have a thirty-six inch stroke.

60 Mounted transversely of the frame 1 below the runner 3 is a shaft 34, which carries a gear segment 35 at each side of the runner 3 in mesh with a rack-bar 36 on the respective side of the runner, said rack-bars 65 being disposed to overhang the respective

segments 35, as shown, while the member 35 is referred to as a gear segment it will be understood that a rack pinion or other suitable means may be used if desired. Mounted on one end of the shaft 34 without the frame 1 are three gears 37, 38 and 39, the gear 37 being loose on the shaft and the gears 38 and 39 being keyed thereto. The gear 37 is shown, in the present instance, as being loosely mounted on a sleeved end of 70 the hub-gear 38, as shown in Fig. 3. The gear 38 has a pin 40 projecting therefrom and carrying a block 41, which is mounted for free movement in a segmental slot 42 in the gear 37 for the purpose hereinafter described. The gears 37 and 39 are driven by pinions 43 and 44, respectively, on the drive shaft 26, and the gear 39 is slightly larger than the gear 37 and is provided at a predetermined point in its periphery with a gap 39^a whereby the drive pinion 44 is freed from driving connection with the gear 39 during a portion of each cycle of movements of the mechanism. The drive pinion 43, on the other hand, remains in permanent 80 mesh with the gear 37 and effects a constant driving of such gear. The gear 38 meshes with and drives a gear 45 on the shaft of the cylinder 5, said gears 38 and 45 being in the proportion of two to one to impart a 85 double rotation to the cylinder 5 at each complete rotation of the gear 38.

The pinion 44 may be considered as a rotatable part, receiving its power from any suitable source, and is so termed in some of 90 the claims.

The gap 39^a of the gear 39 is so positioned that the pinion 44 will be freed from the gear 39 during the period of mesh of the segments 35 and rack-bars 36, which takes 105 place during the period of contact of the cylinder with the type form on the bed. It is thus evident that during this impression period the bed and cylinder will be caused to have synchronous movements due to both 110 receiving their movements from the movements of the runner 3—the bed through the medium of the racks and pinions 31, 32 and 33, and the cylinder through the rack-bars 36, segments 35, shaft 34 and gears 38 and 115 45. There will, however, during this period of uniform movement of the bed and cylinder be a slight difference in rotation between the gears 37 and 39 due to the gear 37 being driven at a constant speed from the shaft 120 26 while the gear 39 is driven at a varying speed from the movement of the runner 3. This difference in movement between the gears 37 and 39 is permitted by reason of the block 41 of the gear 38, which latter gear 125 is in fixed connection with the gear 39, moving in the slot 42 of the gear 37. Inasmuch as the speed of rotation of the gear 39, when driven from the runner 3, is more rapid than the speed of rotation of the gear 37, 130

the block 41 will move forward in the slot 42, the length of such slot being so proportioned that the block will move in contact with the forward end wall thereof at the time the segments 35 and rack-bars 36 move out of mesh. The pinion 44 by this time will have traversed the gap 39^a, and at approximately the instant of disconnecting of the segments 35 and racks 36, will move into mesh with the teeth of the gear 39 at the finishing end of the gap. The contacting of the block 41 with the forward end wall of the slot 42 at approximately the instant of moving into mesh of the pinion 44 and gear 39 causes a lining up or registering of the gears 37 and 39 so that there will be no clash between the teeth of the pinion 44 and gear 39 as they move into mesh.

In order that the block 41 may be returned to the rear end of the slot 42 when the gear 39 is being driven by the pinion 44, the gear 39 is slightly larger than the gear 37, thus causing it to be driven at a slightly slower speed than the constantly driven gear 37. The contacting of the block 41 with the rear end wall of the slot 42 is timed to take place at approximately the instant the pinion 44 passes from engagement with the teeth of the gear 39 and at the instant of initial engagement of the segments 35 with the rack-bars 36, thereby effecting such a lining up or registering of the differentially movable segment 35 and rack-bars 36 that there will be no clash between the teeth thereof as they move into engagement.

From the foregoing, it will be apparent that the gear 37 has no function as a driving member for any of the movable parts of the mechanism, but acts solely as a registering member which coacts twice in each cycle of operation of the mechanism with the gear 38 through the medium of the block 41 and slot 42, to effect a registering of the teeth of the pinion 44 and gear 39 as they move into mesh, and a registering of the teeth of the segments 35 and rack-bars 36 as they move into mesh, at different points in a cycle of movement of the gears.

In the operation of my improved mechanism, it will be understood that each of the gears 23, 37, 38 and 39 make one complete revolution for each cycle of operations of the press, or, in other words, at each two revolutions of the cylinder 5, and the drive pinions 25 and 43 are proportioned accordingly with respect to the gears with which they mesh. It will thus be understood that both the gears 23 and 37 are constantly driven at a fixed speed from the drive-shaft 26. The gear 23 in addition to taking care of the properly timed raising and lowering movements of the cylinder 5 to move it into and out of impression position also imparts a variable reciprocatory movement to the runner 3. The variable reciprocatory movement

which is imparted to the runner 3 is communicated to the bed 4 through the pinions 31 and rack-bars 32 and 33 whereby the bed is moved synchronously with the runner 3, but has its strokes double the length of the 70 strokes of said runner. When the bed 4 during the impression stroke thereof has moved approximately to impression position, the pinion 44 will enter the gap 39^a of its gear, thus disengaging said gear, and the segments 35 will move into initial engagement 75 with the respective racks 36 and remain in engagement with such racks until the bed has reached the end of the impression receiving portion of its stroke.

The engaging of the segments 35 and racks 36 and the disengaging of the pinion 44 with its gear 39 causes a driving of the cylinder from the movement of the runner 3 so that the bed and cylinder during the impression portion of the stroke of the former will have synchronous movements. When the bed has finished the impression portion of its stroke the segments 35 will turn out of engagement with the racks 36 and the pinion 44 will move into engagement with the teeth of the gear 39 at the finishing end of the gap 39^a, the disengaging of the segments and racks and the engaging of the pinion and gear teeth taking place at approximately the same time so that the pinion 44 will commence its driving action on the gear 39 instantly upon the disengaging of the segments 35 with their racks. At approximately the instant of initial engaging 100 of the segments 35 with the respective rack-bars 36, the block 41 will make contact with the rear end wall of the slot 42 in the registering gear 37 and properly register the gears 37 and 38 so that the segments will 105 move smoothly into mesh with the racks 36 without any clash of the teeth thereof. The driving of the gears 38 and 39 from the runner 3 during the impression portion of the bed stroke causes said gears to rotate more rapidly than the gear 37 and effects a consequent advancing of the block 41 in the slot 42 of the gear 37. This advance is sufficient to cause the block 41 to move into contact with the forward end wall of the slot 110 42 at approximately the instant of disengaging of the segments 35 with the racks 36 and the engaging of the pinion 44 with the gear 39 at the finishing end of the gap 39^a thereof to effect a proper registering of the gears 37 and 39 so that the pinion 44 will 115 move smoothly into engagement with the teeth of the gap-gear. The slight enlarging of the gap-gear 39 and the reducing of the pinion 44 over the gear 37 and pinion 43, respectively, causes the gap-gear, when driven by its pinion, to rotate a little slower than the gear 37 and effect a return of the block 41 to the rear end of the gear slot 42, this relative rotation being so proportioned 120

125

130

that the block 41 will move into contact with the rear end of the slot 42 at approximately the instant of disengaging of the pinion 44 with the gap-gear 39 and the engaging of the segments 35 with the racks 36, for the purpose hereinbefore described.

It is evident that I have provided a simple and efficient mechanism for driving the cylinder and bed at different speeds during portions of the strokes of the bed and for automatically effecting a driving connection between the bed and cylinder at a predetermined point in a movement of the bed, and maintaining such connection and a consequent uniform speed of drive of the bed and cylinder during a predetermined portion of one stroke of the bed at each cycle of operations of the press.

It is also evident that the drive pinion 44, gears 38, 39 and 45 form a means for communicating rotation to the cylinder 5 from the source of power which, in the present instance, may be considered as the shaft 26; that the rack and pinion or segment 35 and 36, shaft 34 and gears 38 and 45 form a separate means for communicating rotation to the cylinder from the bed driving means of which latter the slide 3 forms a part, and that said separate cylinder driving means have parts in common, namely the gears 38 and 45.

I wish it understood that my invention is not limited to any specific construction, arrangement or form of the parts, as numerous modifications of the mechanism and the parts thereof may be made without departing from the spirit of the invention.

Having thus described my invention, what I claim as new, and desire to secure by Letters Patent, is:—

1. In combination, a reciprocatory bed, a rotatable cylinder, means for imparting reciprocatory movements to the bed, means for intermittently driving the cylinder, and means independent of the bed and periodically operable through a portion of said cylinder driving means to drive the cylinder from said bed driving means synchronously with the movement of the bed.

2. In combination, drive means, a reciprocatory bed, a rotatable cylinder, means actuated by said drive means for reciprocating said bed, means independent of the bed and operable to periodically connect said bed driving means with said cylinder to cause the cylinder to rotate at a speed which is synchronous to the movement of the bed during a predetermined portion of its movement, and means operable in conjunction with a part of said cylinder driving means to drive the cylinder when not being driven from the bed driving means.

3. In combination, a reciprocatory bed, a rotatable cylinder, means for reciprocating said bed, means operable by said bed

reciprocating means to periodically drive said cylinder at a speed which is synchronous with a portion of the movement of said bed, said cylinder driving means having in part a pair of coacting gears, and means operable to drive said coacting gears to rotate the cylinder when said cylinder driving means is not being driven by said bed driving means.

4. In combination, drive means, a reciprocatory bed, a rotatable cylinder, means actuated by said drive means for driving said bed, a shaft, geared connection between said shaft and cylinder, and separate means alternately operable one to drive said shaft from said bed driving means and the other to drive said shaft from said first mentioned drive means.

5. In combination, a reciprocatory bed, a rotatable cylinder, drive means for said bed, means for driving said cylinder at one speed during a portion of a cycle of operations, and means independent of the bed operable in conjunction with a part of said cylinder driving means and actuated by said bed driving means for driving the cylinder synchronously with the bed during a portion of the movement of the latter and when said first mentioned cylinder driving means is disconnected.

6. In combination, a reciprocatory bed, a rotatable cylinder, drive means for said bed, means periodically operable to drive said cylinder from said bed driving means to cause a synchronous movement of the cylinder and bed, said cylinder driving means having rack and pinion parts which engage at a predetermined point in a cycle of operations, and means operable through a part of said cylinder driving means to drive the cylinder when not being driven from the bed driving means.

7. In combination, a reciprocatory bed, a rotatable cylinder, bed driving means, a rotatable drive part, and means operable independently of the bed to periodically connect said cylinder with first one and then the other of said bed driving means and part to impart predetermined rotation at intervals to said cylinder.

8. In combination, a reciprocatory bed, a rotatable cylinder, bed driving means, a rotatable drive part, and means periodically operable to connect first one end and then the other of said bed driving means and drive part with said cylinder, the connection between said bed driving means and cylinder being independent of the bed and causing the cylinder to have a movement synchronous to the bed movement.

9. In combination, a reciprocatory bed, a rotatable cylinder, a drive shaft, means having connection with and driven by said shaft for imparting predetermined reciprocatory movements to said bed, and mecha-

5 nism operable to periodically close the driving connection with said cylinder first through one and then the other of said shaft and bed driving means independent of the bed, the bed and cylinder having synchronous movements when the cylinder is being driven from the bed driving means.

10 10. In combination, a reciprocatory bed, a rotatable cylinder, a primary drive means, a bed driving means connected to and driven from said primary means, and mechanism operable to periodically close the driving connections to said cylinder first through one and then the other of said primary and 15 bed driving means independently of the bed, the bed and cylinder having synchronous movements when the cylinder is being driven from said bed driving means.

11 11. In combination, a reciprocatory bed, 20 a rotatable cylinder, a primary driving means, a bed driving means having connection with and driven from said primary means, a shaft, a plurality of gears connecting said shaft and cylinder for communicating rotation from one to the other, a gap-gear on said shaft, a pinion driven by said primary means and meshing with said gap-gear whereby said shaft is intermittently driven from said primary means 25 through the pinion and gap-gear, and means operable to drive said shaft from said bed driving means when the driving of the shaft by said primary means is interrupted.

12 12. In combination, a reciprocatory bed, 30 a rotatable cylinder, bed driving means, mechanism for periodically driving said cylinder, means having rack and segment parts acting through a part of said mechanism and operated by said bed driving 40 means to drive the cylinder at a speed synchronous to the movement of the bed when the cylinder driving action of said mechanism is interrupted, and means operable to register the periodically engaging parts of 45 said cylinder driving means and mechanism to prevent clash as they move into engagement.

13 13. In combination, a reciprocatory bed, a rotatable cylinder, a primary drive means, 50 a bed driving means connected to said primary means, means independent of the bed operable to alternately connect the cylinder with first one and then the other of said primary and bed driving means, and means 55 for registering said cylinder driving means with the respective coacting driving parts of said primary and bed driving means to prevent clash therebetween as they respectively engage said cylinder driving means.

60 14. In combination, a reciprocatory bed, a rotatable cylinder, bed driving means, a shaft, a cylinder-gear and a gap-gear fixed to said shaft, connection between said cylinder-gear and cylinder, means for intermittently driving said gap-gear, and means for

driving said shaft from said bed driving means when the driving of said gap-gear is interrupted.

15 15. In combination, a reciprocatory bed, a rotatable cylinder, bed driving means, a shaft, connection between said shaft and cylinder for communicating rotation from one to the other, a gap-gear carried by said shaft, means for intermittently driving said gap-gear, means for communicating rotation to said shaft from said bed driving means when the driving of said gap-gear is interrupted, and means for effecting a registering of said gap-gear and the drive means therefor and a registering of the parts of 80 said shaft driving means when they respectively move into driving connection.

16 16. In combination, a reciprocatory bed, a rotatable cylinder, a drive shaft, a driven shaft, means for driving said bed from a 85 rotation of said drive shaft, connection between said driven shaft and cylinder for driving one from the other, a gap-gear fixedly carried by and a registering gear loosely carried by said driven shaft, means actuated by said drive shaft for continually driving said registering gear at a constant speed and for intermittently driving said gap-gear, rack and segment means operable to communicate rotation to said driven shaft 90 from said bed driving means when the driving of said gap-gear is interrupted, and means cooperating with said registering gear to cause a registering of the parts of 95 said rack and segment means when they move into engagement.

17 17. In combination, a reciprocatory bed, a rotatable cylinder, a primary driving means, means for driving said bed from said primary means, separate means having parts 105 in common for alternately communicating rotation to said cylinder from said primary driving means and said bed driving means, means for registering the parts of said cylinder driving means which periodically 110 make and break communication.

18 18. In combination, a reciprocatory bed, a rotatable cylinder, a primary driving means, means for driving said bed from said primary means, separate cylinder driving 115 means having parts in common for alternately making and breaking driving connection first with said primary driving means and then with said bed driving means, and means having a part continually driven 120 at a constant speed by said primary means and operable to register the separable parts of said cylinder driving means as they respectively move into driving engagement.

19 19. In combination, a reciprocatory bed, a rotatable cylinder, a primary driving means, means for driving said bed from said primary means, a shaft, connection between said shaft and cylinder for driving one from the other, a gap-gear fixed to said 125

- shaft, a registering gear loose on said shaft, drive pinions for said registering and gap-gears and forming parts of said primary driving means, said gap-gear being different 5 in size from said registering gear, rack and segment means operable to engage and to impart rotation to said shaft from movements of said bed driving means when the gap-gear is inactive by reason of its drive 10 pinion traversing the gap thereof, and means connecting said registering gear and shaft for registering the gap-gear and its drive pinion when they move into engagement and for registering the rack and segment parts of said shaft driving means when they move into engagement.
20. In combination, a reciprocatory runner member, means for driving said member, a bed carried by said member for reciprocatory movements relative thereto, means for communicating relative reciprocatory movements to said bed from said member, a rotatable cylinder, mechanism operable to communicate interrupted rotation to said 25 cylinder, and means having parts in common with said mechanism and operable to communicate rotation to the cylinder from said member when the driving of the cylinder by said mechanism is interrupted.
30. 21. In combination, a reciprocatory runner member, a bed reciprocally movable relative to said member, means for driving said runner member, means for communicating relative reciprocatory movements to 35 said bed from said member, mechanism operable to communicate interrupted rotation to said cylinder, and means having rack and pinion parts in common with said mechanism for imparting rotation to the cylinder
- 40 from movements of said runner member when the driving of the cylinder by said mechanism is interrupted.
22. In combination, a reciprocatory runner member, means for driving said member, a bed carried by said member for reciprocatory movements relative thereto, means for imparting reciprocatory movements to said bed from lesser reciprocatory movements of said member, a rotatable cylinder, a shaft, means connecting said shaft and cylinder for imparting rotation from one to the other, means for imparting interrupted rotation to said shaft, and means 45 operable to connect said shaft and runner member to communicate movement from one to the other when the driving of the shaft by said first mentioned shaft driving means is interrupted.
50. 23. In combination, a reciprocatory runner member, means for imparting reciprocatory movements to said member, a bed reciprocally movable relative to said member, means for communicating movements to said bed from movements of said member, a rotatable cylinder, a shaft, connection between 55

said shaft and cylinder for imparting rotation from one to the other, a gap-gear fixed to said shaft, a drive pinion for said gap-gear, means having rack and segment gears for interengaging and connecting said member and shaft to drive the shaft from said member when said pinion is traversing the gap in the gap-gear.

24. In combination, a reciprocatory runner member, means for driving said member, a reciprocatory bed, means for imparting movements to said bed from said runner member, a rotatable cylinder, a shaft, connection between said shaft and cylinder for imparting rotation from one to the other 80 and separate means for alternately driving said shaft to impart continuous rotation thereto, one of said shaft driving means having connection with and operable by a reciprocation of said runner member.

25. In combination, a reciprocatory runner member, drive means for said member, a bed mounted over said runner member for reciprocatory movements relative thereto, means for imparting relative reciprocation to said bed from said member, a rotatable cylinder, a shaft, connection between said shaft and cylinder for communicating rotation from one to the other, separate means for operating in alternate 95 order to impart continuous rotation to said shaft, one of said means being actuated by movements of said runner member, and means operable to register the parts of said separate shaft driving means when they 100 respectively move into driving connection.

26. In combination, a reciprocatory runner member, drive means for said member, a bed mounted for reciprocatory movements over said runner member and relative thereto, means for imparting reciprocatory movements to said bed from said runner member, the strokes of the bed being longer than the strokes of said member, a rotatable cylinder, separate means having parts in common and being alternately operable to impart continuous rotation at variable speeds to said cylinder, one of said separate means being periodically actuated by said runner member to cause the cylinder to have uniform movements with said bed during the period of driving of the cylinder from said member.

27. In combination, a reciprocatory runner member, drive means for said member, a bed mounted for reciprocatory movements over said runner member and relative thereto, means for imparting reciprocatory movements to said bed from said runner member, the strokes of the bed being longer than the strokes of said member, a rotatable cylinder, separate means having parts in common and being alternately operable to impart continuous rotation at variable speeds to said cylinder, one of said separate 125

- means being periodically actuated by said runner member to cause the cylinder to have uniform movements with said bed during the period of driving of the cylinder from said member, and means automatically operable to positively register inter-engaging parts of each of said separate cylinder driving means as they respectively move into cylinder driving engagement. 5
10. 28. In combination, a reciprocatory runner member, a bed mounted for reciprocatory movements relative to said member, means for driving said bed from movements of said member, a rotatable cylinder, a drive means, means connecting said drive means to said cylinder and operable to impart interrupted rotation thereto, means actuated by said member and having parts in common with said last mentioned means 15 to drive said cylinder when the driving of the same by said drive means is interrupted, and means automatically operable to register the different parts of the respective cylinder driving means as they move into 20 driving connection. 25
29. In combination, a reciprocatory runner member, a bed movable by said member relative thereto, a rotatable cylinder, means having separable parts which are operable 30 to periodically engage and connect said member and cylinder to impart movement from one to the other thereof, and means automatically operable to register the separable parts of said connecting means as they 35 move into driving engagement. 30. In combination, a reciprocatory runner member, a bed movable by said member relative thereto, a rotatable cylinder, means for connecting said member and cylinder 40 and having rack and pinion parts which periodically engage and break engagement to effect an intermittent driving of the cylinder by said member, and means for registering the rack and pinion parts of said connecting means as they move into engagement. 45
31. In combination, a reciprocatory member having a series of rack teeth lengthwise thereof, a bed movable by said member relative thereto, a shaft, a pinion rotatable with said shaft and adapted to periodically engage with and be driven by the rack teeth on said member, a rotatable cylinder, connection between said shaft and cylinder for imparting rotation from one to the other, and means for registering the teeth of said pinion and member as they move into driving engagement. 50
32. In combination, a rotatable cylinder, a drive shaft, a driven shaft, means connecting said drive shaft and cylinder through said driven shaft and having parts which periodically make and break connection to communicate intermittent rotation to the cylinder through a continuous rotation of 55
- said drive shaft, and means continuously driven by said drive shaft and coöperating with said cylinder driving means to register the separable parts of said driving means as they move into driving connection. 70
33. In combination, a rotatable cylinder, a drive shaft, a driven shaft, gears for communicating rotation from said drive shaft to said cylinder and carried in part by said driven shaft, said gears being operable to 75 make and break connection between said drive shaft and cylinder to interrupt the driving of the cylinder, a gear loosely carried by said driven shaft and having pin and slot connection with one of said gears 80 whereby the gears so connected are permitted to have limited relative rotation, and a pinion carried by said drive shaft and acting to continuously drive and coöperate with said loose gear to effect a registering 85 of said make and break gears as they move into driving connection. 90
34. In combination, a driven shaft, a gap gear and a continuous tooth gear fixedly carried by said shaft and one being larger than the other, a loose gear carried by said shaft and having a segmental slot, a part 95 movably projecting into said gear slot and standing in fixed relation to the gears which are fixed to said shaft, a cylinder, connection between said continuous toothed gear and said cylinder, a drive shaft, and pinions on said drive shaft, one for driving said gap gear and the other for driving said slotted gear, said slotted gear and part 100 co-operating to act on said gap gear to register the teeth thereof with the respective pinion teeth when moving into register at the finishing end of the gear gap. 105
35. In combination, a rotatable cylinder, a shaft, gears connecting said shaft and cylinder for imparting rotation from one to the other, a gap-gear on said shaft, a drive pinion for said gap-gear, and means independently of the teeth of said gears and automatically operable to register the teeth of said pinion and gap-gear as they move into 110 engagement at the finishing end of the gear-gap. 115
36. In combination, a reciprocatory member having a series of longitudinally extending rack teeth, a rotatable cylinder, a shaft, connection between said shaft and cylinder for imparting rotation from one to the other, a pinion, a gap-gear and a registering gear mounted on said shaft, the latter only being loose with relation to the shaft, and the pinion having periodical engagement with the rack teeth on said member 120 whereby rotation is communicated to the shaft at intervals from movements of said member, a pair of fixedly connected drive pinions one for driving engagement with said registering gear and the other for driving engagement with said gap-gear, said 125 130

drive pinions imparting differential rotation to said registering and gap-gears and said first mentioned pinion and rack teeth imparting reverse differential rotation to said 5 registering and gap-gears and being operable to have driving engagement one with the other when the gap gear and its pinion are disengaged, and means automatically operable by the differential movements imparted to said registering and gap-gears by said rack teeth and pinion to place the teeth of the gap-gear and its pinion in register when moving into engagement and operable by the differential movements imparted to 10 said gears by said drive pinions to place said rack teeth and the teeth of the coating pinion in register when moving into engagement.

37. In a printing press of the class described, a reciprocatory bed, a rotatable cylinder, mechanism having a runner part operable to reciprocate said bed, means operable to periodically raise said cylinder from and lower it to impression position with respect to said bed, means operable to drive said cylinder and to break driving connection therewith when the cylinder is in impression receiving position, and means periodically operable by the runner part of said 25 mechanism to communicate rotation to said cylinder from said mechanism when the cylinder driving connection of said first means is interrupted.

38. In a printing press of the class described, a reciprocatory runner member, a bed reciprocally movable on said runner member, a rotatable cylinder over said bed, mechanism for communicating reciprocatory 30

movements to said runner member, means for periodically raising and lowering said cylinder to place it into and out of impression position with respect to the bed, means for communicating reciprocatory movements to said bed from movements of said member, means operable to drive said cylinder and to 40 periodically break its driving connection therewith, and means having parts in common with said cylinder driving means and operable by said runner member at predetermined points in its reciprocatory movement to drive said cylinder when its driving connection with said first cylinder driving means is broken, whereby the cylinder is caused to have uniform movements with the bed during a portion of its impression stroke. 45 50 55

39. In combination, a reciprocatory bed, a rotatable cylinder, primary drive means, a bed driving means connected to and driven from said primary means, said bed driving means having a reciprocally movable part 60 which moves at a speed differential to the bed speed, and mechanism independent of the bed operable to periodically close the driving connection to said cylinder first through said primary means and then 65 through the reciprocatory part of said bed driving means, the bed and cylinder having movements in unison when the cylinder is being driven from said bed driving means. 70

In testimony whereof, I have hereunto signed my name to this specification in the presence of two subscribing witnesses.

MICHAEL A. DROITCOUR.
